By *Samuel W. Balch*
Attorney.

UNITED STATES PATENT OFFICE.

DANIEL B. GEDDES, OF NEWARK, NEW JERSEY.

ANTIRATTLER FOR WINDOWS.

1,385,208.

Specification of Letters Patent. Patented July 19, 1921.

Application filed December 3, 1920. Serial No. 427,991.

To all whom it may concern:

Be it known that I, DANIEL B. GEDDES, a citizen of the United States of America, and a resident of Newark, county of Essex, State 5 of New Jersey, have invented certain new and useful Improvements in Antirattlers for Windows, of which the following is a specification.

This invention has for its object to provide 10 an anti-rattler for windows or doors to keep them from being shaken by the wind, the anti-rattler being adapted to be inserted between the sash and bead or between two sashes to prevent rattling. A further object 15 is to provide a device which is efficient, inexpensive, which can be readily used, and which will not mar the window sash or frame.

In the accompanying sheet of drawings 20 which forms a part of this application,

Figure 1 is a perspective of an anti-rattler which embodies this invention.

Fig. 2 shows its application to a window.

Fig. 3 is an edge view.

25 Fig. 4 shows the blank of sheet metal from which the anti-rattler is formed.

The anti-rattler comprises an upper leaf spring 5 and a lower leaf spring 6, the length of each of which is preferably greater than 30 the width. The upper spring is preferably slightly shorter than the lower spring and overlies the lower spring so that its forward margin as well as its ends will be back of the forward margin and ends of the lower 35 spring. The two springs are bowed so that they will bear together at their ends and will be normally separated in between. A branch 40 the other and are joined together most conveniently by reason of their being the two

ends of a strip of sheet metal which is folded over into a loop. The springs are also preferably joined to the branches or loop by being of one piece of sheet metal therewith 45 and all formed from a single stamping.

A length of chain 8 has one end engaged in the bend of the loop and serves to connect the anti-rattler with a hook in the window frame so that it will not be lost when not in use. 50

For insertion between the bead and window frame the branches are pinched together in the fingers and this flattens the two leaf springs against each other so that they can be inserted and as the lower spring 55 projects beyond the upper spring the edges of the upper spring are kept from scratching the window frame. The loop is bent out of the plane of the springs when flattened together so that it will be spaced away from 60 the window frame and convenient to handle.

I claim,

1. An anti-rattler for windows comprising two bowed leaf springs which bear together at their ends and each of which has a 65 transverse branch from its middle, the two branches being connected to hold the springs together, substantially as described.

2. An anti-rattler for windows comprising two bowed leaf springs which bear together 70 at their ends, and a loop each of the ends of which connects with the middle of one of the leaf springs to hold the springs together, substantially as described.

3. An anti-rattler for windows comprising 75 two bowed leaf springs which bear together at their ends, the upper spring being smaller than the lower spring, and a loop each of the ends of which connects with the middle of one of the leaf springs to hold the springs 80 together, substantially as described.

DANIEL B. GEDDES.
